UNITED STATES PATENT OFFICE.

WILLIAM RAY YARLOTT, OF DETROIT, MICHIGAN.

SPARK PLUG.

Application filed November 16, 1923. Serial No. 675,175.

To all whom it may concern:

Be it known that I, WILLIAM RAY YARLOTT, a citizen of the United States, residing at Detroit, in the county of Wayne and 5 State of Michigan, have invented new and useful Improvements in Spark Plugs, of which the following is a specification.

The present invention relates to improvements in spark plugs for use with internal 10 combustion engines, and has, as its object, to provide a construction adapted to prevent the formation of carbon and oil deposits which will short circuit the plug.

The invention seeks to provide an insulation 15 for the electrodes which will prevent short circuiting when the porcelain core breaks, or when a certain amount of carbon or oil becomes deposited upon the porcelain core.

20 Another object of the invention is to afford a comparatively simple and durable construction, particularly in the means for eliminating checking or cracking of the porcelain, which ordinarily surrounds the 25 central electrode, thus eliminating leakage of current through the wall of the core to the metallic shell.

A further object of the invention is to afford a comparatively simple and very 30 durable construction, particularly in the means for securing in position the ground electrode which is ordinarily directly soldered or secured to the shell.

The above and other objects of the invention 35 are obtained by providing a spark plug comprising, broadly, a metallic shell serving to receive a core or tube of porcelain or other insulating material which encloses an electrode. The shell is provided with a 40 lining of a suitable heat retaining and yielding insulating material, such as mica. This lining is preferably built up from a series of layers of material, such as mica rings, and is constructed to form a seat for 45 the porcelain tube. The spark plug includes a core or tube, preferably of porcelain, having a shoulder which abuts the end of the lining, the latter preventing movement of the tube longitudinally of the shell 50 in one direction. The lining extends preferably not less than an inch and a half through the shell, and being spaced from the porcelain tube or core, provides not only seating means for the core, but, by reason 55 of its retention of heat, serves to prevent the deposit of carbon and oil upon the

core. Moreover, the mica lining, by reason of its retention of heat, prevents rapid cooling of the porcelain core, which tends to check or crack the same. 60

The entire tube is insulated from the shell by means of a lining additional to the one mentioned above, and positioned between the shell and the portion of the tube provided with the shoulder. 65

In the accompanying drawings, there is illustrated, for the purpose of making the invention clear, one embodiment of the same, and in these drawings:

Fig. 1 is an elevational view. 70

Fig. 2 is a longitudinal sectional view.

Fig. 3 is a transverse section on the line 3—3, looking in the direction of the arrows, and

Fig. 4 is a plan view of the ground electrode. 75

Referring to the drawings for a more detailed description, 10 indicates a shell having a shank portion 11 which is threaded, as is usual. An insulating tube or core 12, 80 preferably of porcelain, extends axially of the shell, and has an intermediate portion 13 of enlarged diameter to form an under shoulder 14 and an upper shoulder 15. The core is spaced from the wall of the shell, 85 and is insulated therefrom by means of a lining of suitable yielding and heat retaining insulating material 16 which is preferably built up from a series of superposed rings. Mica is the preferred material, since 90 it retains the heat and readily yields. Furthermore, the construction of the lining from a number of layers or rings of mica improves its yielding qualities. The lower end of the lining is positioned above an inverted flange 17 upon which rests the ground electrode 18. The electrode has a body portion 19, in the form of a split ring, which seats upon the flange and is provided with a terminal portion 20 extending 100 through an opening 21 in the flange. The annular portion of the electrode is flattened, as indicated in Figure 2, and the lining 16 rests thereon. It will be noted that the lining of mica terminates at the shoulder 105 14, the shoulder resting against the end of the lining which prevents movement of the core longitudinally of the shell in one direction. The enlarged intermediate portion of the core may be insulated from the 110 shell by means of a continuation of the lining in the form of a wrapping 22 of in-

sulating material, such as mica, and an in-turned flange 23 at the upper end of the shell serves to compress a gasket 24 to hold the core against upward movement within the shell. It will be, of course, understood that this continuation of the lining in the form of the wrapping 22 is not a necessary feature of the invention, since the porcelain tube will be satisfactorily supported and maintained against cracking if the lining is terminated at the shoulder of the tube.

By reason of the provision of the mica lining 16 and 22, should the porcelain break, there is no danger of short circuiting of the plug due to exposure of the central electrode 25 which extends through the bore of the tube. Moreover, the lining retains the heat for a considerable length of time, and will burn the carbon and oil deposits as well as prevent the rapid cooling of the porcelain core, which has a tendency to check or crack when cooled too rapidly.

It should be observed that the shank of the shell and the lining are of substantial length; preferably the lining extends through the shell for not less than an inch and a half, so that a very considerable firing space is provided, and the distance to be traversed in order to short circuit the spark is approximately six inches.

The mica lining forms a comparatively yielding seat for the rather frangible porcelain core which is a substantial improvement over the unyielding metallic shoulder which is usually provided upon the interior of the shell to serve as a seat for the core. The construction of the lining from a series of layers or superposed mica rings tends to make the seat for the porcelain core more yielding than would be the case were the lining formed from a single piece of mica or similar material.

In addition to the external insulation, or internal insulating lining of mica within the core is provided. It will be observed that the upper portion of the bore is enlarged as at 26, and around the electrode 25 are insulating disks 28 of mica forming a shell which extends from substantially the end of the lining 16 to above the upper end of the shell. By reason of this insulation, should the porcelain crack around the flange 23 the shell will not short circuit the plug. The end of the electrode 25 fits within a connector plug 29 threaded into the upper end of the core.

It should be understood that such modifications may be made in the structure illustrated and described as come within the scope of the following claims.

I claim:

1. In a spark plug, a metallic shell, an insulating tube extending axially through said shell, an electrode within the tube extending longitudinally thereof, the tube be-

ing formed with a shoulder intermediate its ends, and an insulating lining of mica within said shell fitting closely against the wall of the shell and surrounding and spaced from the portion of said tube at one side of the shoulder, said lining forming a seat for said shoulder and serving wholly to hold the tube against movement longitudinally of the shell in one direction.

2. In a spark plug, a metallic shell, an insulating tube of porcelain extending axially through said shell, an electrode within the tube extending longitudinally thereof, the tube being formed with a shoulder intermediate its ends, an insulating lining of mica within said shell fitting closely against the wall of the shell and surrounding and spaced from the portion of said tube at one side of the shoulder, said lining forming a seat for said shoulder and serving wholly to hold the tube against movement longitudinally of the shell in one direction.

3. In a spark plug, a metallic shell, an insulating tube extending axially through said shell, an electrode within the tube extending longitudinally thereof, the tube being formed with a shoulder intermediate its ends, an insulating lining of mica within said shell fitting closely against the wall of the shell and surrounding and spaced from the portion of said tube at one side of the shoulder, said lining forming a seat for said shoulder and serving wholly to hold the tube against movement longitudinally of the shell in one direction, an in-turned flange at one end of said shell serving to support said lining, and a ground electrode having a substantially annular portion supported on said flange between the same and said lining.

4. In a spark plug, an insulating tube of frangible material extending axially through said shell, an electrode within the tube extending longitudinally thereof, the tube being formed with a shoulder intermediate its ends, an insulating lining of mica within said shell surrounding and spaced from the portion of said tube at one side of the shoulder, said lining forming a seat for said shoulder and serving wholly to hold the tube against longitudinal movement of the shell in one direction, and an interior lining of insulating material within the tube between the same and said electrode, said interior lining extending from substantially on a line with said tube shoulder past the end of the shell above said shoulder.

5. In a spark plug, a metallic shell, an insulating tube of porcelain extending axially through said shell, an electrode within said tube, said tube being formed with a shoulder intermediate its ends, an insulating lining of yielding heat retaining material within said shell, said lining being

built up from a series of superposed layers and being formed to afford a seat for said shoulder adapted to hold the tube against movement longitudinally of the shell in one direction, said lining supporting the tube out of contact with the shell.

6. In a spark plug, a metallic shell, an insulating tube of porcelain extending axially through said shell, an electrode within said tube, said tube being formed with a shoulder intermediate its ends, an insulating lining of mica within said shell, said lining being built up from a series of superposed layers and being formed to afford a seat for said shoulder adapted to hold the tube against movement longitudinally of the shell in one direction, said lining supporting the tube out of contact with the shell.

10 7. In a spark plug, a metallic shell, a porcelain insulating tube extending axially through said shell, an electrode extending through said tube, the tube having an intermediate portion of enlarged diameter to form upper and lower shoulders, means at one end of the shell for holding the tube against longitudinal movement in one direction, an insulating lining of mica within the shell around the tube and spaced from the tube, said lining extending from one end of the shell to the lower shoulder of said tube and engaging said shoulder to hold the tube against movement in the other direction, said lining wholly holding the tube against movement of the shell, and a second electrode on said shell.

15 8. In a spark plug, a metallic shell, a porcelain insulating tube extending axially through said shell, the tube having an intermediate portion of enlarged diameter to form upper and lower shoulders, a flange at one end of the shell extending inwardly over the upper shoulder to hold the tube against movement in one direction, a flange at the other end of the shell, an insulating lining resting upon said last mentioned flange and extending through the shell around the tube and spaced from the tube to said lower shoulder, the lining forming a seat at said lower shoulder, and the shoulder abutting said seat whereby the tube is held against movement in the other direction longitudinally of the shell, said lining serving to support the tube out of contact with said shell, an electrode extending through said tube, and a second electrode at the lower end of the shell.

20 9. In a spark plug, an insulating tube of frangible material extending axially through said shell, an electrode within the tube extending longitudinally thereof, the

tube being formed with a shoulder intermediate its ends, an insulating lining of mica within said shell surrounding and spaced from the portion of said tube at one side of the shoulder, said lining forming a seat for said shoulder and serving wholly to hold the tube against longitudinal movement of the shell in one direction, and an interior lining of insulating material within the tube between the same and said electrode, said interior lining extending from substantially the upper end of said lining past the end of the shell above said shoulder.

25 10. In a spark plug, a metallic shell, an insulating tube of frangible material extending axially through said shell, an electrode within the tube extending longitudinally thereof, the tube being formed with the shoulder intermediate its ends, an insulating lining of mica within said shell extending substantially throughout the entire length thereof, said lining being formed intermediate its ends with a shoulder forming a seat for said tube shoulder and below the tube shoulder serving to surround the portion of said tube and being spaced from said portion of the tube, said lining serving wholly to support and hold the tube against movement longitudinally of the shell in one direction, and an interior lining of insulating material within said tube between the same and the electrode extending from the upper end of said lining past the adjacent end of the shell.

30 11. In a spark plug, a metallic shell, a porcelain insulating tube extending axially through said shell, an electrode within the tube, a lining of yielding heat retaining insulating material within the shell and extending substantially throughout the length thereof, said lining completely insulating said electrode from the shell.

35 12. In a spark plug, a metallic shell, a porcelain insulating tube extending axially through said shell, an electrode within the tube, a lining of yielding heat retaining insulating material within the shell, said lining serving wholly to support the tube out of contact with the shell against movement longitudinally of the shell in one direction.

40 13. In a spark plug, a metallic shell, a porcelain insulating tube extending axially through said shell, an electrode within the tube, a lining of mica within the shell, said lining serving wholly to support the tube out of contact with the shell against movement longitudinally of the shell in one direction.

45 In testimony whereof I have hereunto set my hand.

WILLIAM RAY YARLOTT.
